UNITED STATES PATENT OFFICE.

JOHN A. BARNES, OF WEST NEW BRIGHTON, NEW YORK, ASSIGNOR TO THE SUPER-HEATER COMPANY, OF NEW YORK, N. Y., A CORPORATION OF DELAWARE.

SUPERHEATER.

1,400,853.

Specification of Letters Patent. Patented Dec. 20, 1921.

Application filed November 7, 1917. Serial No. 200,691.

To all whom it may concern:

Be it known that I, JOHN A. BARNES, a citizen of the United States, residing at West New Brighton, county of Richmond, 5 State of New York, have invented certain new and useful Improvements in Super-heaters, of which the following is a specification.

My invention relates to superheaters of 10 the type commonly referred to as fire tube superheaters, and has for its purpose the production of a superheater of this type, wherein a future addition of superheating surface may be readily made without necessitating any material alteration or any 15 discarding of the parts installed in the first place.

The invention will be readily understood 20 from the following description, which is to be read in connection with the accompanying drawings forming part hereof. In these drawings, Figure 1 shows a view of a section on line I—I of Fig. 2, and Fig. 2 a sectional view taken on line II—II of Fig. 25 1 of a superheater as first installed according to my invention; Fig. 3 shows a sectional view on line III—III of Fig. 4, and Fig. 4, a sectional view on line IV—IV of Fig. 3, illustrating the addition of more units; Figs. 30 5 to 8, are similar views of a modification, the section being taken respectively on lines V—V, VI—VI, VII—VII, and VIII—VIII; Fig. 9 shows a side view and Fig. 10 a bottom elevation of the header; Figs. 11 35 and 12 show similar views of a modified header.

Taking up now a detailed description of the invention, and referring first to Figs. 1 and 2, we have here illustrated an ordinary form of fire tube superheater as applied to a Scotch marine boiler. The flues 1 have extending into them the loops 2' of the superheater units 2, there being two loops to each unit, extending into neighboring flues. One end of each unit is attached to and communicates with the chamber 3 of the header 4, and the other end with chamber 5. Fig. 2 illustrates four rows of flues occupied by superheater loops. It will be understood that substantially all of the flues in the first four vertical tiers, counting from the header outward, are supplied with such loops. The flues beyond the fourth (not shown) have no loops in them. The figure 55 shows only those superheater units on the

left side of the header. It will be understood that there are units, symmetrical with those shown, on the right side, connected to the right side of the header at the openings 6.

Referring for a moment to Fig. 9, which is a side view from the right of a complete header, it will be seen that the tops of the chambers 3 and 5, are provided with flanges 7 and 7' respectively. These flanges are for 60 the purpose of attaching steam pipes to the two chambers, the one supplying the wet steam from the boiler being attached to chamber 3 and the other, conveying the superheated steam to the engine, to chamber 5. 65 The two chambers are usually made separate and secured to each other by means of the straps 8, screwed to their sides by means of cap screws 9.

The action of the superheater may be described as follows. Steam, entering chamber 3 from the boiler, leaves this chamber and circulates through the units 2, being delivered by them to chamber 5, whence it is carried to the engine. While circulating 80 through the units 2 it becomes superheated by the hot gases which are flowing through the flues on their way from the firebox to the stack.

It happens occasionally that for certain 85 reasons it may be undesirable at the time a superheater is installed to make it of the size really possible and generally advisable as far as the size of the boiler and number of its flues are concerned. With such an 90 undersized superheater the superheat given the steam for a given rate of steam consumption will be less than is required for best economy. When later on conditions are altered and a higher degree of superheat is 95 wanted, the only practicable thing with appliances as hitherto known is to remove the old superheater and install an entirely new one, having either more units or units with more loops each. The present invention 100 makes it possible to install the additional superheating surface without making it necessary to discard any of the old material, or even to alter it. In other words, the old superheater units may be used in substantially 105 the shape they are, all that is necessary being to connect them up differently and then to put in the additional units.

To make this possible there is provided, as an integral part of chamber 3, a blind 110

passage 10, which is closed at top and bottom, as evident from Fig. 9. A plug 11 at the bottom closes the opening provided to remove the core used in casting. In the 5 superheater as originally installed this passage 10 is not utilized. To increase the superheater to the desired size, as shown in Figs. 3 and 4, the ends of the units 2 are detached from chambers 3 and 5 and connected anew as shown in Fig. 3. Those 10 ends which were connected to chamber 3 are now connected to blind passage 10, while the remaining ends of one set of units now connect with chamber 3, and the other with chamber 5. This leaves one tier of openings 15 in chamber 3 free and also one tier in chamber 5; and to these openings are now connected the new units 12. The new units 20 12 are seen to comprise four loops each, and these loops occupy the next four tiers 25 of flues adjacent to the four occupied by the old units.

Tracing the course the steam will take in the enlarged superheater, it will be seen that 25 it passes from chamber 3 to chamber 5 by two "parallel" paths. The one takes it through the original units 2, one set carrying the steam from chamber 3 to chamber 10, the other carrying it from chamber 10 to chamber 5. The other of the two parallel 30 paths is through the new units 12. It will be noted that each of these two parallel paths comprises four loops, and that moreover the "steam section", *i. e.*, the total 35 free area for the flow of steam, has remained what it was before the new units 12 were added. Both of these features are highly desirable from practical considerations.

It will be understood that while I have 40 described the installation of the additional units on the one side of the header only, a corresponding installation is made on the other side, so that the total superheating surface becomes double what it was in the 45 first place. Obviously the degree of superheat attained after the change is materially higher than it was before.

In Figs. 5 to 8 I show a similar superheater, the only difference being that the units 50 2 each comprise three loops, while the new units 12 comprise six. With this exception the two forms are alike, and *mutatis mutandis*, the description given with reference to Figs. 1 to 4 applies equally well to Figs. 5 to 8. 55 It will be evident that other modifications may be made. The header may, *e. g.*, be located to one side or above or below the flues, in which case there are superheater units attached to only one side of the header; or the header might be placed at some other than a right angle to the flue sheet; or the units might be altered to conform to a staggered flue arrangement; or the loops of the units in the form illustrated might lie vertically instead of horizontally; but these and

similar variations are obvious and are considered to be within the spirit of the appended claims.

Figs. 11 and 12 illustrate a variation that may be made in the header. Instead of having the chamber 10 cast integral with chamber 3, it may be made as a separate casting; in which case it need not be supplied until the enlargement of the superheater is undertaken. It is then secured to the other two 75 chambers by means of the straps 8 as shown.

While the forms of the header shown are those preferred by me, some variations may evidently be made without departing from the inventive idea and the spirit of the sub- 80 joined claims.

What I claim is:—

1. In a superheater of the class described, the combination of a header provided with three chambers, a set of superheater elements connecting the first and second chambers, a second set of elements connecting the first and third chambers, and a third set of elements connecting the third and second chambers. 90

2. A superheater comprising a single three-chambered header, each chamber provided with the same number of openings for the attachment of superheater units, two of the chambers being provided with connections for steam supply and delivery respectively. 95

3. A superheater comprising a single header having three chambers each provided with the same number of openings for the attachment of superheater units, two of them provided with connections for steam supply and delivery respectively, and units communicating with a plurality of said chambers through the openings. 100

4. In a superheater of the class described, the combination of a header provided with three chambers, a set of superheater elements connecting the first and second chambers, a second set of elements connecting the first and third chambers, and a third set of elements connecting the third and second chambers, the number of elements in the three sets being substantially the same. 110

5. In a superheater of the class described, the combination of a header provided with three chambers, a set of superheater elements connecting the first and second chambers, a second set of elements connecting the first and third chambers, and a third set of elements connecting the third and second chambers, the total superheating surface of the set connecting the first and third chambers being substantially equal to the sum of the superheating surfaces of the other two 120 sets. 125

6. In a superheater of the class described, the combination of a header provided with three chambers, a set of superheater elements connecting the first and second cham- 130

bers, a second set of elements connecting the first and third chambers, and a third set of elements connecting the third and second chambers, the number of elements in the three sets being substantially the same, the total superheating surface of the set connecting the first and third chambers

being substantially equal to the sum of the superheating surfaces of the other two sets.

JOHN A. BARNES.
